UNITED STATES PATENT OFFICE.

ADOLPH I. ANDERSON, OF ZUMBROTA, MINNESOTA.

SILO.

Application filed July 25, 1923. Serial No. 653,793.

To all whom it may concern:

Be it known that I, ADOLPH I. ANDERSON, a citizen of the United States, residing at Zumbrota, in the county of Goodhue and

5 State of Minnesota, have invented new and useful Improvements in Silos, of which the following is a specification.

My present invention has reference to silo construction, and has for its primary 10 object to produce a frost-proof silo.

A further object is to simplify and improve the existing art by constructing a silo whose outer wall is of hollow tile and which has an inner wall of plastic material arranged directly against the outer wall for a distance from the top and bottom thereof and from thence spaced inwardly from said outer wall to provide a dead air space therebetween, and to further hang in the 20 dead air space sheets of insulating material which will positively prevent dampness entering the silo.

A still further object is to produce a silo comprising inner and outer walls, the 25 former being erected after the completion of the outer wall and wherein the outer wall is of reinforced hollow tile provided at certain of its longitudinal joints with inwardly extending bolts designed for engagement 30 with bendable cleats and also for supporting sheets of insulating material between the cleats and the outer wall, said cleats having secured thereon metal laths over which is spread a cement plaster, said cleats terminating a suitable distance from the top and bottom of the outer wall, but the plaster is continued over the inner face of all portions of the wall.

The drawings which accompany and form 40 part of this application illustrate a satisfactory embodiment of the improvement reduced to practice, and wherein:

Figure 1 is a vertical sectional perspective view of a silo construction in accordance 45 with this invention.

Figure 2 is a horizontal sectional view in a line with one of the horizontal joints of the outer wall section showing the lath supporting strips before the same are bent to engage with the bolts or rivets.

Figure 3 is a fragmentary sectional view substantially similar to Figure 1, showing the strips bent and the metal lath secured thereon.

55 The remaining figures illustrate details. My improved silo may be erected at only

a slightly greater cost than that of ordinary cement or masonry silos and when erected is practically indestructible.

Because a certain amount of ensilage in 60 silos is used before extremely cold weather arrives, and also to reduce the cost of my silo construction, the dead air space between the walls thereof is arranged a desirable distance from the top and bottom of the 65 silo.

Referring now to the drawings in detail, the numeral 1 designates the outer wall of the silo. The outer wall is constructed of courses of hollow tile laid in cement and 70 which have their confronting surfaces preferably provided with interengaging means. In addition to this, the wall construction 1 is reinforced by metal rods prior to the insertion of the cement through the hollow 75 body of the tiles. In the course of erection of the outer wall I arrange in certain of the horizontal joints of the tile bolt members 2 which project a suitable distance beyond the inner face of the wall. By reference to the 80 drawings it will be seen that the upper course of bolts are disposed a suitable distance from the top of the wall 1 and the lower series a less distance from the bottom of the wall 1. These bolts are designed to 85 provide suspending means for sheets of insulating paper 3, the said sheets having lapping ends and edges so that the same completely surround the wall 1.

The bolts 2 are designed to be passed 90 through openings in bendable wooden strips 4. The strips are in straight condition before being arranged on the bolts which materially facilitates the erection of the silo. When bent the strips will conform in contour to the inner surface of the wall 1, but the said strips are held spaced from the said wall 1. If desired, the threaded ends of the bolts may be reduced to provide shoulders against which the inner faces of 95 the strips 4 contact, or any suitable spacing means may be provided between the strips and the outer wall 1. The ends of the bolts which project through the strips may be flattened by force from a hammer or may be 100 engaged by nuts. As a matter of fact in lieu of the bolts 2, rivets or other analogous elements may be employed.

Sustained against the innermost sheet of insulating material by the elements 2 there 110 are metal laths, the said laths receiving thereon one or more coatings of plastic ce-

ment 6. The cement is also plastered on the wall 1 above the uppermost and below the lowermost strips 4 and the joints between the plastered inner face of the wall 1 and the laths are beveled or rounded to present no sharp corners. The plastic inner face of the silo is smooth throughout so that no obstruction will be offered to the ensilage.

The double wall construction affords a 10 dead air space to prevent frost entering the silo. The sheets of insulating material 3 prevent the passage of moisture between the walls, and it is believed that the foregoing 15 description, when taken in connection with the drawings will fully set forth the construction and advantages of my improvement to those skilled in the art to which such inventions relate.

Having described the invention, I 20 claim:—

1. A silo construction comprising a reinforced outer wall of hollow tile, inwardly projecting elements thereon, sheets of insulating material suspended from said elements and disposed in spaced relation and 25 with their vertical and horizontal edges

overlapping, strips secured to said elements and between the spaced sheets, said strips being rounded to conform to the inner contour of the outer wall, metal lathing secured to the innermost sheet of insulating material by means of said projecting elements and a plastic facing on said metal lath. 30

2. A silo construction comprising a reinforced outer wall of hollow tile, inwardly 35 projecting elements thereon, sheets of insulating material suspended from said elements and disposed in spaced relation and with their vertical and horizontal edges 40 overlapping, strips secured to said elements and between the spaced sheets, said strips being rounded to conform to the inner contour of the outer wall, metal lathing secured to the inner most sheet of insulating material by means of said projecting elements, 45 a plastic facing on said metal lathing and also on the inner face of the silo above and below said metal lath.

In testimony whereof I affix my signature.

ADOLPH I. ANDERSON.
